UNITED STATES PATENT OFFICE.

SAMUEL MORRIS LILLIE, OF PHILADELPHIA, PENNSYLVANIA.

EVAPORATING APPARATUS.

972,880.

Specification of Letters Patent. Patented Oct. 18, 1910.

Application filed December 21, 1906. Serial No. 348,850.

To all whom it may concern:

Be it known that I, SAMUEL MORRIS LILLIE, of the city and county of Philadelphia, State of Pennsylvania, have invented an improvement in Evaporating Apparatus, of which the following is a specification.

My invention has reference to evaporating apparatus and consists of certain improvements which are fully set forth in the following specification and shown in the accompanying drawings which form a part thereof.

The object of my invention is to provide means for heating the fresh liquor to be evaporated or concentrated prior to its entering the evaporating circulation in the several effects of the multiple effect, said heating being performed by the steam or vapor in the steam chambers of one or more of the several effects, whereby the fresh liquor is in condition for speedy and economical concentration or evaporation upon entering the circulation in the evaporating chambers of the effects.

My invention may be employed in what is known as the "Lillie" evaporating apparatus, preferably of the vapor reversible type, one form of which is herein shown, or may be adapted to any other type of evaporating apparatus.

My invention consists in providing the steam chambers of the several effects of a multiple effect with heating coils or devices connected in series, combined with means to supply the liquor to one end of the series of coils or devices, and means for causing it to pass from the said coils or heating devices into the evaporating system of the apparatus.

My invention also comprehends the above apparatus when further combined with means for reversing the course of the vapors and liquor, or either of them, in a reversible multiple effect whereby the liquor may be caused to flow in the proper direction through the coil to suit the reversal operations of the evaporating apparatus and the uses to which the apparatus is put.

My invention also comprehends other features of construction, which, together with those above specified, are more particularly defined in the claims and will be better understood by reference to the drawings, in which:

Figure 1 is a plan view of a "Lillie"

multiple effect with my improvements applied thereto; Fig. 2 is a sectional elevation of the same near the front end; and Fig. 3 is a sectional elevation in simple form showing the application of my improved liquor heating and circulating pipes.

A, A', A², are three effects of a multiple effect. In Figs. 1 and 2 they are shown with their steam ends arranged alternately at opposite ends of the apparatus. The adjacent ends of the several effects are connected by passages which are controlled by suitable valves for circulation of the vapors and for reversing the direction or passage of the vapors. Thus the steam chamber S of effect A is connected with evaporating chamber of effect A' by passage B which is controlled by a valve C; and the said evaporating chamber of the said effect A' is connected with the steam chamber S of the effect A² by a passage B' controlled by a valve C'. These valves C and C' are connected by a rod D and adapted to be moved by a motor M or other means for opening one valve and closing the other, or vice versa. Likewise the steam chamber S of the effect A' is in communication with the vapor chambers of the two outer effects A A² by passages B³ and B² which have valves C³ and C² respectively and said valves are operated by a rod D' moved by a motor M' or otherwise so that the valves are closed and opened alternately. Steam is supplied by valve T to effect A or by valve T' to effect A² and exhaust or vacuum takes place by valve T³ from effect A² and by valve T² from effect A according to the direction of circulation. The operation of a reversible multiple effect of this character is fully set out in my application Ser. No. 322,190 filed June 18, 1906 and no claim is made to it herein.

The liquor to be concentrated is fed to the effects and circulated therein in much the same way as set out in my application aforesaid, but my improved manner of heating the said liquor before it enters the evaporating chambers of the effects embodies novel features and to which claim is made herein.

In view of the fact that the multiple effect evaporating apparatus herein shown is a reversible system it becomes advisable to provide means for reversing the flow of the fluid to be evaporated and such is shown in the accompanying drawings.

As the multiple effects shown in Figs. 1 and 2 have the adjacent effects turned in opposite directions and include the pumps with consequent complication, I have provided a diagrammatic view in Fig. 3 to illustrate the general features of my invention.

In Fig. 3, A, A' and A² are the effects and show the steam chamber ends at S. In these steam chambers are suitable heaters such as coils of pipe E which are preferably connected in series so that the liquor that traverses them becomes heated by the surrounding steam. Assume valves H, J, J⁶, J⁷ and J⁹ are open and valves H', J¹⁰ and J⁸ closed; the cold liquor is supplied by pipe G and passes through valve H to the coil or heater of coolest effect A and leaves the coil of the hottest effect A², passes thence by pipe I into the evaporating chamber of effect A², thence by pipe I⁰ into the evaporating chamber of the effect A', thence by pipe I' in the evaporating chamber of effect A, thence by pipe I² to discharge. The liquor in each effect is treated to a circulation by the pumps and concentration by evaporation, so that it is gradually more dense or concentrated as it passes through the several effects. It will seem that, the liquor being highly heated before entering the evaporating chambers of the effects, is in a most excellent condition for economical concentration and for this reason the capacity and efficiency of the plant is materially increased without additional expense.

When the effects are to be reversed, the valves H and J⁹ and J are closed, and valves H', J¹⁰ and J⁸ opened, in which case the cold liquor passes by pipe G' in the coil or heater E of effect A² and thence through coils E of the other effects, thence through pipe I² into the evaporating chamber of effect A and successively through the evaporating chambers of the succeeding effects A', A² and discharges by pipe I' and valve J⁸. It is evident that if the effects are not made for reversal the liquor may be made to flow always in one direction with corresponding simplification of pipes and valves.

Now that the general manner of circulation has been explained by reference to Fig. 3, the application of the pipes to the apparatus shown in Figs. 1 and 2 will be more readily understood. Looking at Fig. 2, we see the interior of the steam chambers S in the effects A and A² and the interior of the evaporating chamber in effect A'. A² is the hottest effect and A is the coolest effect. The coils or heater E in the steam chambers are connected in series by the pipes F and the opposite ends of these series of coils or heaters are connected respectively with supply pipe G having valve H and supply pipe G' having valve H', one of which valves only is open at any one time.

The bottom of the evaporating chambers

are provided with circulating pumps L for the liquor as set out in my Letters Patent No. 789,159 dated May 9, 1905. The interior arrangement of the several effects may be of the construction shown in said Letters Patent No. 789,159 and also as shown in Letters Patent No. 777,114 dated December 13, 1904, and Patent No. 939,143 dated November 2, 1909, all of which relate to the same type of apparatus herein described and illustrated.

The liquor, after being heated in the coils or heater E, is passed by pipe I through a valve J into an automatic valve controlled case K from which it flows into the evaporating chambers of the hottest effect A². It then enters the fluid under the circulation of the pump L of said effect. If the level of the liquor in the effect A' becomes too low due to its concentration, part of the liquor from effect A² is forced by the pump through pipe I⁰ and valve J⁴ and admitted by the automatic valve in case K to the evaporating chamber of the effect A'. This liquor is then absorbed in the liquor being circulated by the pump L of this effect. In like manner when the level of the liquor in the evaporating chamber A is too low, the pump of effect A' forces liquor by pipe I² through valve J² and this is admitted by the automatic valve in casing K into the effect A. The concentrated liquor from the effect A may be discharged by pipe I⁶ having valve J⁹ and through which it is forced by the pump. During this operation the valves H', J', J⁶, J⁸ and J⁹ have been closed and the other valves are open. When the liquor is to be circulated in the reverse direction these valves are to be opened and valves H, J, J², J⁴ and J⁰ are to be closed. The automatic valves in cases K are preferably float valves of any ordinary type, and may be similar, if desired to the float valves shown at R in the steam chambers S for controlling the escape of water of condensation.

By providing a pipe W having a valve W' it is evident that the liquor to be evaporated may be made to reverse its direction of flow through the heaters of the several steam chambers to correspond to the reversal of the vapors in the effects and yet flow through the evaporating chambers of the several effects continually in the same direction. This condition is sometimes required. The use of this pipe W will also enable the apparatus to be used in cases where the liquors are to circulate in the reverse direction to the flow of the vapors and corresponding to the flow through the heaters, these different manners of handling the liquors being well understood in "Lillie" multiple effect evaporating apparatus. It also frequently happens that a multiple effect apparatus is used with several independent liquors, each evaporated or con-

centrated in its own effect, but the vapors of all such liquors but that of the last effect are utilized in maintaining the temperature of the effect as a whole. My invention is in-
5 tended to apply to all these uses of the apparatus and such others as might arise and are capable of being carried out.

I have shown the coils E constituting the heaters in excellent form for maximum duty
10 and simplicity as to construction. Moreover, they are capable of easy removal for cleaning and while removed may be substituted by a bridging pipe or temporary coil. The inlet and outlet terminals E' E²
15 are flanged and secured to the walls of the cylindrical shell in fixed position and the heater coils have flanged ends which fit upon and are bolted to said inlet and outlet flanged terminals as at e. These heaters may
20 be made in any other form and, though perhaps not so desirable, may be made as a permanent part of the interior structure of the effect and to be heated by the steam in the steam chamber thereof. By making
25 them of coiled pipe, copper tubing may be used without excessive cost of construction.

I do not restrict my invention to the reversible feature, as it is equally effective in those types of multiple effects in which the
30 effects are not reversible. It is also to be understood that the particular type of multiple effects herein shown is given as that to which I more particularly apply my invention but it is to be taken as only an example
35 of a suitable multiple effect and any other type of multiple effect may be employed in lieu thereof without departing from the spirit of my invention.

Having now described my invention what
40 I claim as new and desire to secure by Letters Patent, is:

1. In a multiple effect evaporating apparatus the combination of a series of effects each having a steam chamber and an evaporating chamber provided with evaporating tubes, with a heater independent of the evaporating tubes of the effects arranged in the steam chamber of one of the effects, a liquor supply pipe for delivering liquor
45 to the heater, and a system of pipes for conducting the heated liquor from the heater to the evaporating chamber of the effects.

2. In a multiple effect evaporating apparatus the combination of a series of effects each having steam and evaporating chambers, with heaters arranged in the steam chambers and wholly outside of the evaporating chambers of the effects and connected in series, a liquor supply pipe for delivering liquor to the heater of the coolest effect, and a system of pipes for conducting the heated liquor from the heater of the hottest effect to the evaporating chambers
60 of the several effects in succession.

65 3. In a multiple effect evaporating appa-

ratus the combination of a series of effects each having steam and evaporating chambers, with heaters arranged in the steam chambers of the effects and wholly outside of the evaporating chambers, a liquor supply pipe for delivering liquor to the heaters independently of the evaporating chambers, a system of pipes for conducting the heated liquor from the heaters to the evaporating chambers of the effects, means for reversing the direction of passage of the vapors of the several effects, and means for reversing the direction of circulation of the liquor through the heaters to cause it to circulate in the reverse direction to its flow through the effects during evaporation.

4. In a multiple effect evaporating apparatus, the combination of a series of effects operating as a unit, and having circulating liquor pipes for causing the liquor being
85 evaporated to traverse the effects in succession, with means located in a plurality of the steam chambers and outside of the evaporating chamber of the effects for heating the liquor before being delivered to the
90 evaporating chambers of the effects.

5. In an evaporating apparatus, a cylindrical body divided into steam and evaporating chambers, circulating means for circulating the liquor to be evaporated within
95 the evaporating chamber, a heater for the liquor arranged in the steam chamber outside of the evaporating chamber, and means for causing the liquor to flow first through the heater and then into the evaporating
100 chamber, whereby said liquor is first heated by the steam in the steam chamber and then vaporized by the same steam in the evaporating chamber.

6. In an evaporating apparatus, a closed cylinder having steam and evaporating chambers, combined with a heater in the steam chamber outside of the evaporating chamber, a pipe to supply liquor to the heater, and a pipe to convey the heated liquor from the heater into the evaporating chamber whereby the liquor is first heated
110 by the steam in the steam chamber and then evaporated by the steam in the evaporating chamber.

7. In a multiple effect evaporating apparatus, the combination of a series of effects each having steam and evaporating chambers, coils of pipe substantially as shown in addition to the evaporating means of the effect and located in the steam chambers of each of the effects and connected in series, means for supplying liquor to said coils, pumps for circulating the liquor in each effect, means for supplying the heated liquor from the coils to the evaporating chamber of one of the end effects, a pipe leading from the pump of one effect to the evaporating chamber of the next effect and so on to the last effect, and means for drawing off
120
125
130

the liquor from the last effect or that farthest from the one to which steam was initially admitted.

8. In a multiple effect, the combination of a series of effects having means for heating the first effect by steam from an external source and means for causing the vapor of the first effect to heat the second effect and so on according to the number 10 of effects employed, heaters in the steam chambers of a portion of the effects and in which liquor is to be heated before delivery for evaporation, means to cause the liquor to pass through said heaters in succession 15 and in a direction the reverse of that taken in the apparatus by the vapors and means for delivering the heated liquor to the first effect of the series.

9. In a multiple effect, the combination 20 of the several effects and connecting means for passing the vapors from one effect to the next in the usual manner, combined with heating means in a portion of the effects and heated by the steam or hot vapors existing 25 in the steam chambers of the effects during their normal operation for evaporating liquor, and means to cause the liquor to be

evaporated to flow through the heating means in the direction from the coolest to the hottest heating means and effect. 30

10. In an evaporating apparatus, the combination of a cylinder divided into steam and evaporating chambers, with a removable coil for heating the liquor arranged in the heating chamber, flanged inlet and outlet parts fixed to the shell of the cylinder and forming openings through the same for the supply and discharge of the liquor traversing the coil, detachable flanged joints between the ends of the coil and inlet and outlet located within the steam chamber whereby the coil may be wholly removed and temporarily replaced by another coil during cleaning of the removed coil, and bolts extending through the flanged joints and the 40 flanged inlet and outlet parts for forming detachable steam tight joints between the flanged parts and shell of the cylinder. 45

In testimony of which invention, I have hereunto set my hand.

S. MORRIS LILLIE.
